UNITED STATES PATENT OFFICE.

RICHARD H. MARVIN, OF EAST LIVERPOOL, OHIO, ASSIGNOR TO THE R. THOMAS AND SONS COMPANY, OF EAST LIVERPOOL, OHIO, A CORPORATION OF OHIO.

INSULATOR.

1,245,940.

Specification of Letters Patent. Patented Nov. 6, 1917.

Application filed May 11, 1916. Serial No. 96,832.

To all whom it may concern:

Be it known that I, RICHARD H. MARVIN, a citizen of the United States of America, and residing at East Liverpool, in the county of Columbiana and State of Ohio, have invented a certain new and useful Improvement in Insulators, of which the following is a specification.

My invention relates to insulators and particularly to insulators of the multiunit type, and the object of my invention is to provide an insulator in which the units are graded to insure a more even voltage distribution than has heretofore been attained.

15 In the accompanying drawings,

Figure 1 is an elevation, in partial section, of a multiunit suspension insulator in which my invention is embodied in one form;

20 Figs. 2, 3 and 4 are elevations, half in section, of the three graded units employed in the insulator shown in Fig. 1, but drawn to a larger scale;

Fig. 5 is a diagram of a suspension insulator with graphic indications of three principal elements of capacity which must be taken into consideration in grading an insulator;

Fig. 6 is a diagram showing the distribution of voltage over a string of ungraded insulators; and

Fig. 7 is a diagram of the distribution of voltage over a string of insulators graded in accordance with my invention.

35 The uneven distribution of voltage along a string of suspension insulators is well known. With a small number of units this feature is not serious and scarcely justifies the complication and expense required to 40 overcome it. But with an increasing number of units, the distribution becomes increasingly poorer, and a limit is soon reached where additional units add very little to the value of the string. With the increase of 45 operating voltages the problem of meeting this phenomenon becomes serious.

In general the unit next to the line has the largest proportion of voltage across it, the succeeding units taking a smaller and 50 smaller amount. This condition is unsatisfactory for two reasons, viz., the units near the line have to stand an excessive strain, while the units near the tower or grounded end of the string have a lower voltage across 55 them than is desirable for efficient service.

The present construction affords simple means by which a more even distribution of the voltage across all the units of the insulator may be attained.

Before taking up the present construction in detail, a word may be said about the theory of grading, reference being had to the diagram Fig. 5. The distribution of impressed voltage along a string of units is determined by the relations between the various capacities involved. These capacities may be divided into four groups. (1) The capacity (C^1) through the porcelain between the cap and stud of each unit, which may be called the internal capacity. (2) 70 The capacity (C^2) between the metal fittings and the earth or grounded objects. (3) The capacity (C^3) between the metal fittings on one portion of the string to those on any other portion, and (4) the capacity (not indicated) between the metal fittings and the line wire. Usually only the first two groups are considered, but experiments have indicated that the others have an appreciable effect.

It is readily seen (Fig. 5) that the current to charge all the capacities C^1 , C^2 , C^3 must pass through the capacity C^1 of unit No. 1. The capacity C^1 of unit No. 2 has to supply current to the following C^1 85 capacities but has a smaller number of C^2 and C^3 capacities to charge. Consequently the first unit has a higher voltage across it than the second, and so on. It appears therefore that if we neglect the C^3 capacities, unit No. 7, viz., the grounded unit, will have the lowest voltage across it. The capacities C^3 tend however to make the voltage across the middle unit the lowest, so that the total result is that one of the units 90 near the grounded end, and not the grounded unit, has the lowest voltage across it. This is indicated in Fig. 6 subsequently referred to.

The principle of grading consists therefore in varying the capacities C^1 from unit to unit, so that the voltage across each unit is kept as nearly as possible the same. This means that the unit next to the line must have the greatest C^1 capacity and successive units, decreasing amounts. While this is theoretically the most perfect method since it secures the most perfectly even distribution of voltage, it entails great complication in manufacture. A very greatly im- 100 105 110

proved result over present constructions is attained if the composite insulator is subdivided into several groups of units, the units of each group being of uniform capacity, while the units of one group differ in capacity from the units of the other groups.

In the illustrative embodiment of my invention here indicated, I have shown a suspension insulator 10 having fifteen units, divided into three groups, *a*, *b* and *c*. Each insulator unit is of well known general type having an inverted cup-shaped head 11, outstanding skirt 12, with petticoats 13 depending therefrom. A metallic cap 14 secured by cement 15 to each head, has a perforated split boss 16 between the sides of which enters the downwardly extending perforated shank 17 of the pin 18 cemented within the head 11 and secured to the boss 16 by a cross pin 18.

In order to increase the capacity of the insulators in group *a* I provide the same with an increased metal area above and below the insulator skirt and adjacent cap 14 and pin 18. This metallic area may be formed in various ways, as by means of flanges on the cap and pin, rings of metallic paint, or otherwise, and I have here illustrated merely one method, viz., by means of independent metallic rings 19 and 20. The ring 19 at its inner margin 21 is upturned beneath the lower edge of the cap and enters the cement 15 by which it is held in position. The lower ring 20 is likewise upturned at its inner margin 22 and enters and is held in position by the cement surrounding the pin 18.

In like manner, but to less extent, the capacity of the insulators in group *b* is increased by means of the rings 23 and 24 which are of less external diameter than those of the insulators in group *a*.

While these rings increase the capacity C^2 and C^3 of each unit, they augment particularly the internal capacity C' , as will be readily understood. The rings here shown may be stamped to shape, spun out of sheet metal or otherwise formed. On account of the width of the metal thus added to the insulator, it is necessary to increase the diameter of the skirt 12 of the insulator in order to secure a proper flash-over voltage.

A comparison between a string of ungraded insulators and a string of graded insulators is graphically illustrated in Figs. 6 and 7 respectively. The percentage of the total voltage which is impressed upon each insulator of the string is illustrated in terms of that across the line unit, which always shows the greatest voltage, curve 1. Curve 2 gives the distribution of voltage along the string in per cent of the total voltage. Each successive ordinate is obtained by adding the value of the per cent. of total voltage

across that unit to the preceding ordinate. For a perfectly uniform distribution of voltage this would be illustrated by a straight line (such as 3) from 1 to 15.

The result of grading the same type of unit illustrated in Fig. 6 is shown in Fig. 7. Here the three units next to the line have the largest conducting rings and a high internal capacity. The next five units are of somewhat smaller capacity, while the last seven units have normal capacity without alteration by means of the metal rings. Instead of uniform curves, the result is a broken line formed by joining the curves of each group. Comparison with Fig. 6 shows the manifest improvement obtained. The efficiency of the lowest unit compared to the line unit has been raised from 23.5% to 46.5%, or nearly doubled. This results in reducing the proportion of the total voltage on the line unit from 16.5% to 11%, a reduction of 27%.

Obviously the proportions of the capacities and the number of units in each group may be variously altered and that shown is merely an illustrative embodiment of the invention, and I do not limit thereto what I claim as my invention.

I claim as my invention:—

1. A multi-unit insulator, comprising a plurality of insulator units of like type but graded to predetermined different capacities increasing as the units approach the conductor carried by the insulator.

2. A multi-unit insulator, comprising a plurality of groups of insulator units, the units of one group differing in capacity from the units of other groups, and increasing as the groups approach the conductor carried by the insulator, for the purpose specified.

3. A multi-unit insulator, comprising a plurality of groups of insulator units of like type, the units of one group having a predetermined capacity different from the capacity of the units of another group, and greater as the groups approach the conductor carried by the insulator, for the purpose described.

4. An insulator unit having metallic cap and pin, and an interposed insulating skirt, in combination with metallic bands respectively overlying and underlying said insulating skirt and extending outward from the cap and pin areas of the insulator a less distance than said insulating skirt, for the purpose described.

5. An insulator unit having metallic cap and pin and an interposed insulating skirt, in combination with independent metal rings respectively overlying and underlying said insulating skirt and extending outward from the cap and pin areas of the insulator a less distance than said insulating skirt, for the purpose described.

6. A multi-unit insulator, comprising a plurality of insulator units each having a metallic cap and pin and interposed insulating skirt and metallic bands respectively overlying and underlying said insulating skirt and extending outward from the cap and pin areas of the insulator, the extent of the metallic bands being greater in the units approaching the conductor carried by the insulator.
7. A multi-unit insulator, comprising a plurality of groups of insulator units each having a metallic cap and pin and interposed insulating skirt, and metallic bands respectively overlying and underlying said insulating skirt and extending outward from the cap and pin areas of the insulator, the extent of the metallic bands being constant for the insulators of each group but varying in different groups but being greater as the groups approach the conductor carried by the insulator, for the purpose described.
8. An insulator unit having cup-shaped head and outwardly extending flange or skirt integral therewith, metallic cap and pin respectively cemented upon and within said head, in combination with independent metallic rings overlying and underlying respectively said skirt and embedded at their margins in the cement uniting the cap and pin to the insulator head.
9. A multi-unit insulator comprising a plurality of insulator units of the metallic cap and pin type, together with auxiliary metallic elements associated with at least some of said units to increase the normal capacity of those adjacent the conductor carried by the insulator.
10. A multi-unit insulator comprising a plurality of insulator units of the metallic cap and pin type, together with auxiliary metallic elements associated with at least some of said units to increase, by graduated steps, the normal capacity of those adjacent the conductor carried by the insulator.
11. A multi-unit insulator comprising a plurality of groups of insulator units of the metallic cap and pin type, together with auxiliary metallic elements of like size for the units of each group, but differing in the different groups and serving to increase the normal capacity of the units of each group, the capacity of the units of the group adjacent the conductor carried by the insulator being greater than that of the units of a more remote group.
12. A multi-unit insulator comprising a plurality of groups of insulator units of the metallic cap and pin type, together with auxiliary metallic elements associated only with those units approaching the conductor carried by the insulator and serving to increase the normal capacity of said units.
13. A multi-unit insulator comprising a plurality of interconnected insulator units and metal disks interposed between adjacent units toward the conductor-carrying end of the insulator for increasing the electrostatic capacity of the insulator units adjacent the conductor.
14. A multi-unit insulator comprising a plurality of interconnected insulator units and metallic disks of varying capacity interposed between adjacent units toward the conductor carrying end of the insulator for increasing the electrostatic capacity of the insulator units adjacent the conductor, the disks of greater capacity being nearer the conductor.
15. A multi-unit insulator comprising a plurality of interconnected insulator units and metallic disks varying in diameter interposed between adjacent units toward the conductor carrying end of the insulator for increasing the electrostatic capacity of the insulator units adjacent the conductor, the disks of greater diameter being nearer the conductor.
16. A multi-unit insulator comprising a plurality of interconnected insulator units and conducting members interposed between said insulator units, said conducting members varying in capacity and being of greater capacity nearer the conductor carried by the insulator.
17. A multi-unit insulator comprising a plurality of interconnected insulator units and conducting members interposed between said insulator units, said conducting members varying in diameter, and those of greater diameter being nearer the conductor carried by the insulator.
